PUNCH

John T. Ferry, Ilion, N. Y., assignor to Remington Rand Inc., Buffalo, N. Y., a corporation of Delaware

Application October 21, 1943, Serial No. 507,071

14 Claims. (Cl. 164—114)

This invention relates to new and useful improvements in the operation of summary card punch devices when associated with tabulators.

The object of the invention is to enable the movement of the wheels of the accumulator in the tabulator to control the movement of certain selected elements of the summary punch card device, said elements being, for example, the punch setting slides.

Generally considered, the invention, in one form, has to do with an accumulator in which the wheels move from a normal to an operative position and when this movement takes place a device is operated which places a controlling element in operative relation to certain slides of the summary punch to preferably prevent their movement.

More particularly the invention may be applied to a tabulator and summary punch in which the tabulator is of the type in which certain accumulators thereon are of the direct subtraction form and move from normal in either of two directions. Means are associated with the accumulator thus moved to operatively actuate certain locking elements on the summary punch so that when the accumulator moves in one direction a certain set of slides is locked out and when the accumulator moves in the other direction another set of slides is locked out.

The general mechanism of the two machines, apart from the invention, is set forth in Patent 2,354,549, to A. G. Rindfleisch, issued July 25, 1944, and entitled "Card controlled mechanism," and particular reference may be had to Figs. 2 and 7 thereof.

A present preferred form which the invention may assume is illustrated in the accompanying drawings in which

Fig. 1 is a partial cross sectional elevation of the tabulator and the associated summary punch, with the parts in normal position;

Fig. 1a is a view, on reduced scale, of parts of the summary punch disposed to the right of Fig. 1;

Fig. 2 is an enlarged side elevation of parts of the tabulator and card punch machine elements with some parts in operated position;

Fig. 3 is a vertical section taken along the line 3—3 of Fig. 2, showing the parts in normal position;

Fig. 4 is a similar section taken along the line 4—4 of Fig. 2, showing the parts in normal position;

Fig. 5 is a cross section of Fig. 1 taken on line 5—5 showing an elevation of the unit in the lower

part of Fig. 2 and looking toward the tabulator;

Fig. 6 is a cross section of Fig. 1 taken on line 6—6 looking toward the summary punch; and,

Fig. 7 is a horizontal section taken along the line 7—7 of Fig. 2, showing the parts in normal position.

In the drawings, there is shown the combination of a tabulator and summary punch mechanism somewhat similar to the combination shown in the above mentioned Rindfleisch patent. As shown and described therein, there is a series of sectors 65 adapted to be positioned by the tabulator and sensed by the punch setting slides 76 of the summary card punch, which slides position an interponent member 167 in selective relation to the punch setting means so as to actuate the punches 141 in accordance with the stepped position of the sector 65 sensed.

In this application and improvement, the rear 20 accumulator wheels 51 (see Fig. 7 of Patent 2,354,549) are adapted to be positioned for addition or subtraction by the movement thereof through the intermediary of a link 316 (see Fig. 3 of the instant case). According to this improvement, this link 316 is provided at its upper end with a special screw or head 60, preferably attached to the link closely adjacent the right-hand frame 61 of the tabulator.

A bracket plate 62 is attached to the outside 30 of the frame 61 and supports a vertically slidable plate 63 by means of suitable pin and slot connections. This plate is provided with a slot 64 (Figs. 2 and 3 of the instant case) into which projects the screw 60 above mentioned. Since 35 this screw is connected to the link 316 which controls the operation of the rear accumulator of the tabulator, preferably the last direct subtraction unit of the tabulator, it is obvious that it moves up and down with the corresponding movement of said accumulator. Where the accumulator is part of a direct subtraction unit, it may be moved from a normal inactive position to either an adding or a subtracting position. When the accumulator is an ordinary one it is moved from a normal inactive position only to an adding position.

When the rear accumulator is moved to the adding position, the screw 60 is moved to the position shown in full lines in Fig. 2, which positions the plate 63 as shown. This plate has a notch along one edge into which fits the end of a short lever 80 pivoted at 81 on the bracket plate 62. The other end of this lever is connected to one end of a spring 82, the other end of which 50 is connected to the bracket plate 62 at 83. This

lever and spring arrangement is preferably of the dead center type, so that when the plate 63 is moved to one position, such as the down position, the spring 82 tends to hold it there, and when it is moved to the upper position from normal, the spring likewise tends to hold it there also.

The plate 63 is moved upward or downward from a normal position so that it will act as an intermediary in the action of locking out one or the other of two sets of punch slides 76 as will be later set forth in detail. To achieve this result the plate 63 is provided with an operating slide plate 84 (Fig. 7) provided with slots 85 into which extend pins 86 dependent from bent-over lugs 87 on the plate 63. A pin 87' on the lower face of the plate 84 connects with a spring 88, the other end of which is connected to one of the pins 86, thus tending to hold the plate 84 to the left in an inoperative position. It is, therefore, apparent that this slide plate 84 is moved up or down to different levels by the vertical movement of the plate 63. It is, however, to be noted that in either of the levels to which it is moved, the plate 84 must be capable of being moved horizontally to project it forward to effect certain results to be later described. This projection of the plate 84 (Fig. 2) is effected by forming an upturned finger 89 on its outer end adapted to be engaged by a roller 90 mounted on the upper end of a lever 91 pivoted at 92 on the bracket plate 62. The lower end of this lever 91 is connected to a link which is composed of two sections 93 and 94 adjustably connected by means of pin and slot connections. The link 94 is provided with a lost motion connection with arm 91 comprising a slot and spring which holds the link biased to the right as shown in Fig. 1. This link is connected at its other end to an operating arm 92' which is adapted to be operated by the front total shaft of the tabulator. The spring connection of link 94 with arm 91 permits operation of said total shaft at times without operating the roller 90.

The arm 92' (Fig. 1) is pivoted at 95 and is connected below the pivot point to link 96 which extends forward and is connected in any suitable manner to the front total shaft of the tabulator. It is sufficient to say that when this total shaft is operated to initiate the taking of a total, the link 96 is moved to the right and this movement takes up the lost motion in link 94 and rocks the roller 90 against the finger 89 and tends to move slide plate 84 to the right from its normal retracted position.

Depending upon the level to which the plate 63 has been moved, the operating slide plate 84 is adapted to move forward and operate one or the other of two arms 97 and 98 which are both pivoted at 99 on the bracket plate 62. In its lower level position, shown in Fig. 2, the slide member 84, when moved forward by the roller 90, engages an adjacent face of the arm 97 and passes under arm 98 and moves said arm 97 around its pivot point 99. When the plate 63 is moved to its uppermost position, it positions the slide plate 84 at its upper level indicated by dot and dash, so that, when the roller 90 moves it forward, it engages the lower end of arm 98 and turns said arm around its pivot point 99. The arm 97 has a notch 100 in its forward edge at the level in which the plate 84 moves when in its uppermost position, so that when the plate 84 is moved forward in its uppermost position, it will move only the arm 98.

There are times when it may be desired to render the plate 84 inoperative, and to achieve this result there is provided a latch finger 101 (Figs. 4 and 5) pivoted at 102 on a portion 103 bent from the bracket plate 62. This latch finger has an ear 104 which projects through a hole in the plate 62 and is adapted to be engaged by a shoulder on a rotatable disc 105. This disc 105 is mounted on a shaft 106 provided with an operating knob 107 and is journaled in a hub 108 extending from the face of the plate 62. When the knob 107 is in one position, the disc 105 through 104 positions the latch finger 101 in front of the finger 89 on the slide plate 84 to prevent said plate from moving forward. When the knob 107 is in the other position, its shoulder engages the ear 104 and moves the same to pivot the latch finger 101 and move it out of the path of finger 89 on slide plate 84 as shown in Fig. 4, thus allowing said plate 84 to have its normal forward and backward movements. Therefore, when the plate 84 is thus latched in inoperative position by the finger 101, the tendency of roller 90 to act on the plate 84 is made ineffective, and under these circumstances the spring connection between the link 93 and lever 91 will permit the total shaft to operate without moving the roller 90.

When either arm 97 or 98 is pivoted around its axis by the operation of the slide plate 84, said arms are adapted to engage arms 109 and 110, respectively, connected to a shaft 111 journaled in the bracket plate 112 which forms part of the frame 113 of a summary punch mechanism disposed normally adjacent the tabulator as shown in Fig. 1. Operated respectively by means of arms 109 and 110 are arms 114 and 115 secured to the shaft 111 on the other side of the bracket plate 112 and these, in turn, are respectively connected to links 116 and 121. These links at their upper ends are connected to arms 117 and 122, which are connected to pivoted bail frames 119 and 123 pivoted at 118 on a bracket plate 125 fastened to the frame of the summary card punch. The outer ends of these bail frames 119 and 123 are provided with dependent locking fingers 120 and 124 which, when the bail frames are operated, are disposed to lie in front of the sets of summary-punch-setting slides 76 so as to prevent their ordinary forward operative movement.

Generally contemplating the operation of the device, it will be perceived that as long as the knob 107 is in one position, the finger 101 is disposed to prevent the operative movement of the slide plate 84. However, when this knob is moved to the other position, this finger is removed and the plate 84 is in condition to be moved to actuate either of the arms 109 and 110 by the roller 90 whenever the total shaft is operated. Which arm the plate 84 actuates depends upon the vertical position of the plate 63 and this, in turn, is determined by the position of the accumulator wheels, whether they are in adding or subtracting position. If the plate 63 is in its lower or adding position, then the forward movement of plate 84 will actuate arm 109 and through this the lock finger 120, whereas if the plate 63 is in its upper or subtracting position, the slide plate 84 will actuate the arm 110 and by means of it will set the lock finger 124 to prevent operative movement of another set of punch setting slides 76.

It is obvious from the above that a device of this character has many uses. However, a specific example would be in obtaining summary

cards of credit or debit totals. If the direct subtraction accumulator is in the adding position, it might be only desirable to set up debit totals in the summary punch. Therefore, the slide 84 will rock arm 109 and through arm 114 link 116 lever 117 will rock the locking finger 120 into position to prevent the slides 76 associated with the credit portion of the summary card from operating. If the slide 84 is positioned in the subtract position (dot and dash in Fig. 2) then finger 120 will remain raised and finger 124 will be lowered to lock out the slides associated with the debit portion of the card.

It will, of course, be apparent that the preferred form of the invention concerns the mechanism wherein the accumulators move to either of two positions from a normal position, but it is also to be remembered that the accumulators may move to only one position from normal. But in any event when they move from normal they effect the locking out of at least one set of punch setting slides as above set forth. In the case of a direct subtraction tabulator, the separate movement of the accumulator wheels to either operative position is adapted to control the locking out of separate sets of punch setting slides as described.

While the invention herein has been described in detail with respect to a present preferred form which the invention may assume, it is not to be limited to such details and forms since many changes and modifications may be made without departing from the spirit and scope of the invention in its broadest aspects. Hence, it is not desired to limit the invention to the particular forms and modifications shown herein, except as the scope of the invention may be limited by the scope of any one or more of the appended claims.

What I claim as new, and desire to secure by Letters Patent, is:

1. In a machine of the class described including a direct subtraction tabulator and a summary card punch, the combination of a direct subtraction unit in the tabulator adapted to be moved from a normal to either an adding or subtracting position, a pair of selector units in the summary card punch, and means controlled by the movement of the direct subtraction unit on the tabulator from one position to another to prevent the selecting action of one or the other of the said selector units dependent upon the movement of the direct subtraction unit of the tabulator.

2. In a machine of the class described including a direct subtraction tabulator and a summary card punch, the combination of a direct subtraction unit on the tabulator adapted to be moved from a normal to either an adding or subtracting position, a plurality of sets of punch setting slides on the summary card punch, and means controlled by the direct subtraction unit and associated with the sets of punch setting slides to prevent the operative movement of one set of slides when the direct subtraction unit is moved to the adding position and to prevent the operative movement of another set of slides when the direct subtraction unit is moved to the subtracting position.

3. In a machine of the class described including a direct subtraction tabulator and a summary card punch, the combination of a direct subtraction unit on the tabulator adapted to be moved from a normal to either an adding or subtract-

ing position, a plurality of sets of punch setting slides on the summary card punch, a total shaft on the tabulator, an operating member positioned by the movement of the direct subtraction unit to one position or another, and means operated by the movement of the total shaft to actuate said operating member, locking members for the sets of punch setting slides, and means disposed between the locking members and the operating member to cause the locking action of said locking members to lock out certain of said sets of slides dependent upon the position of said operating member.

4. In a machine of the class described including a direct subtraction tabulator and a summary card punch, the combination of a direct subtraction unit on the tabulator adapted to be moved from a normal to either an adding or a subtracting position, a slidable plate associated with said subtraction unit, means on the subtraction unit to engage and move the slidable plate in accordance with the movement of the unit, an operating slide on the slidable plate, said slide positioned in accordance with the position of the subtraction unit, a total shaft on the tabulator, means connected to the total shaft and adapted to actuate the operating slide in either of its positions, a plurality of sets of punch setting slides on the summary card punch, locking members for the sets of punch setting slides, and means disposed between the locking members and the operating slide to cause the locking action of said locking members to lock out certain of said sets of slides dependent upon the position of said operating slide, said last named means being operated by said operating slide.

5. In a machine of the class described including a direct subtraction tabulator and a summary card punch, the combination of a direct subtraction unit on the tabulator adapted to be moved from a normal to either an adding or a subtracting position, a slidable plate associated with said subtraction unit, means on the subtraction unit to engage and move the slidable plate in accordance with the movement of the unit, an operating slide on the slidable plate, said slide positioned in accordance with the position of the subtraction unit, a total shaft on the tabulator, means connected to the total shaft and adapted to actuate the operating slide in either of its positions, a pair of sets of punch setting slides on the summary card punch, a locking member connected to each set of punch setting slides, a link connected to each blocking member, an oscillatable lever connected to each link, one of said levers adapted to be operated by the operating slide in one position thereof and the other lever adapted to be operated by the operating slide in another position thereof.

6. In a machine of the class described including a direct subtraction tabulator, the combination of a direct subtraction unit on the tabulator adapted to be moved from a normal to either an adding or a subtracting position, a total shaft on the tabulator, an operating member positioned by the movement of the direct subtraction unit to one operative position or the other, and means operated by the total shaft to actuate said operating member in either of its positions.

7. In a machine of the class described including a direct subtraction tabulator, the combination of a direct subtraction unit on the tabulator adapted to be moved from a normal to either an adding or a subtracting position, a slidable plate associated with said subtraction unit, means on

the subtraction unit to engage and move the slidable plate in accordance with the movement of the unit, an operating slide on the slidable plate, said slide positioned in accordance with the position of the subtraction unit, a total shaft on the tabulator, and means connected to the total shaft and adapted to actuate the operating slide in either of its positions.

8. In a machine of the class described including a summary card punch and a tabulator, the combination of a plurality of sets of punch setting slides on the summary card punch, locking members associated with each set of punch setting slides, selectively operable elements on said tabulator, and means connecting said elements respectively to the locking means whereby the operation of said elements will selectively prevent movement of said sets of punch operating slides.

9. In a machine of the class described including a summary card punch and a tabulator, the combination of a plurality of sets of punch setting slides on the summary card punch, pivoted bails mounted on the punch and adapted when moved to an operative position to prevent the operative movement of said sets of punch setting slides, linkage connected to said bails, and selectively operable pivoted arms associated with and operated by the tabulator, and engageable with said linkage whereby the bails may be operated to selectively prevent movement of one or another of said sets of punch setting slides when the selectively operated arms are actuated.

10. In a machine of the class described including a summary card punch, the combination of a pair of sets of punch setting slides on the summary card punch, pivoted bails mounted on the punch and adapted when moved to operative position to prevent the operative movement of said slides, linkage connected to said bails, a pair of adjacently disposed pivoted arms engageable with said linkage and adapted to be selectively operated to selectively actuate said bails, said arms having engageable portions at different levels, one of said arms being cut away at the

level of the engageable portion of the adjacent arm, whereby a single operating member disposed at different levels can operate one arm and not the other at its different level positions.

11. In a machine of the class described, a frame, a direct subtraction unit disposed adjacent said frame, a bracket plate on said frame, a slidable plate on said bracket plate, an element on said unit engaging said slidable plate and adapted to move it in accordance with the movement of the unit from one operative position to another, an operable element on said slidable plate, a total shaft and means connected to the total shaft to move said operable element in either position of the slidable plate on which it is mounted, a pair of pivoted arms mounted on the bracket plate, and means for causing the operation of one of the pivoted arms by the operable element in one position of the slidable plate and to cause the movement of the other pivoted arm by the operable element in the other position of the slidable plate.

12. In a machine of the class described, the combination of a direct subtraction unit of a tabulator and punch setting slides of a summary card punch, and means controlled by the movement of the direct subtraction unit to selectively prevent the movement of said slides when the unit moves to a predetermined position.

13. In a machine of the class described, the combination of an accumulator unit on the tabulator, and punch setting slides of a summary punch, and means controlled by the movement of the accumulator unit from a normal position to selectively prevent the movement of said slides.

14. In a machine of the class described, the combination of an accumulator unit on the tabulator, and punch setting slides of a summary punch, and means controlled by the direction of movement of the accumulator unit in one direction or another from a normal position to selectively prevent the movement of certain of said slides.

JOHN T. FERRY.
